Inventor

Leonard Brown,

By G. W. Tarnshaw

Attorney

UNITED STATES PATENT OFFICE.

LEONARD BROWN, OF WEBB CITY, MISSOURI; MARY A. BROWN ADMINISTRATRIX OF
SAID LEONARD BROWN, DECEASED.

SAFETY APPLIANCE FOR AUTOMOBILES.

1,274,982.

Specification of Letters Patent.

Patented Aug. 6, 1918.

Application filed January 3, 1917. Serial No. 140,442.

To all whom it may concern:

Be it known that I, LEONARD BROWN, a citizen of the United States, residing at Webb City, in the county of Jasper and

5 State of Missouri, have invented certain new and useful Improvements in Safety Appliances for Automobiles, of which the following is a specification.

10 My invention relates to improvements in apparatus for preventing the operation of an automobile by an unauthorized person.

An important object of the invention is to provide means for rendering the ignition system of the engine inoperative, and to 15 operate a signal, upon the engine being cranked, either by hand or by means of a self-starter.

20 A further object of the invention is to provide apparatus of the above mentioned character, which is convenient to set and reliable in operation.

Other objects and advantages of the invention will be apparent during the course of the following description.

25 In the accompanying drawing forming a part of this specification, is shown a part side elevation and part diagrammatic view of apparatus embodying the invention.

In the drawings, wherein for the purpose 30 of illustration is shown a preferred embodiment of my invention, the numeral 5 designates a support, upon which is pivoted an actuating member or hub 6. The actuating member is provided with a key hole 7 for 35 the reception of the key, not shown, and is adapted to be turned by means of the key and to be locked in the normal position and the open position.

Pivotedly connected with the support 5, as 40 shown at 8, is a horizontally swinging bar 9, to the lower end of which is pivotally connected a friction pulley 10, as shown at 11. When the bar 9 has its lower end swung to the left, the pulley 10 will contact with the 45 fly-wheel 12 of the engine and be rotated thereby. The bar 9 has pivotal connection below its pivot 8 with a link or pitman 13, which is pivotally connected with the lower arm of the actuating member 6. When the 50 actuating member 6 is turned to the right, as shown in the drawing, the pitman 13 will

swing the lower end of the bar 9 to the left, thus bringing the pulley 10 in contact with the periphery of the fly-wheel 12.

Extending longitudinally of the bar 9 and 55 sliding in guides 14 carried thereby is a reciprocating rod 15, the lower end of which is preferably provided with a roller 16, contacting with a cam 17, which is connected with the pulley 10, for rotation therewith. Having suitable pivotal connection with the 60 upper end of the rod 15 is a bell crank lever 18, pivoted to an extension 19, carried by the bar 9. The upstanding arm of the bell crank lever 18 contacts with a shoe 20 formed upon a reciprocating rod 21, operating through 65 stationary guides 22, secured to the support 5. This rod is moved to the right by a spring 21', as shown. The rod 21 has suitable pivotal connection with a bell crank lever 23, 70 pivoted to the support 5, as shown at 24.

The horizontal arm of the bell crank lever 23 carries a contact 25 insulated therefrom and adapted to engage a contact 26 connected with the support 5 and insulated therefrom. 75 Pivotedly connected with the upstanding arm of the hub 6 is a pitman or link 27 having pivotal connection with a bell crank lever 28 which is pivoted upon the support 5, as shown at 29. The bell crank lever 28 80 carries a contact 30 which is insulated therefrom and is adapted to engage a contact 31 secured to the support 5 and insulated therefrom. The horizontal arm of the hub 6 has pivotal connection with a pitman or link 85 32, which is pivoted to a bell crank lever 33. This bell crank lever swings upon a pivot 34. The bell crank lever 33 carries a contact 35 which is insulated therefrom and is adapted to engage a contact 36 carried by 90 and insulated from the support 5.

The numeral 37 designates a magneto, which is connected in a wire 38. One end of this wire has electrical connection with the contact 31. The contact 30 has electrical connection with a wire 39 which is connected with one pole 40 of a switch 41. This switch comprises a swinging contact arm 42, having electrical connection with wire 43. The wire 43 is electrically connected or 100 grounded to the cylinder or cylinders 44 of the engine. Connected with the spark plug

45 of the engine is a wire 46 having the usual coil 47 connected therein. The wire 46 is connected with the wire 38 at the point 48. Connected with the wire 38 at the point 5 49 is a wire 50, having a storage battery 51 connected thereto. The wire 50 has a wire 52 connected therewith, at the point 53 and the wire 52 is connected with the contact 35. The contact 36 has connection with a wire 10 54, connected with the other pole 55 of the switch 41. The wire 50 is connected with the contact 25 and contact 26 is connected with the wire 38, as shown. A bell 56 is connected in the wire 38, as shown.

15 The operation of the apparatus is as follows:

Assuming that the actuating member 6 is in the normal starting position, the contact 30 will then engage contact 31 and contact 20 35 will engage contact 36. If the contact arm 42 is moved to engage the pole 40 of the switch 41 current can then flow from the magneto 37, through a portion of the wire 38, contact 31, contact 30, wire 39, pole 25 40, contact arm 42, wire 43, through the cylinder 44, spark plug 45, a portion of wire 46, coil 47, a portion of wire 46, and through a portion of wire 38 back to the opposite pole of the magneto. By throwing the 30 contact arm 42 so that it engages the pole 55 the magneto will be cut out of circuit and current will then flow from the storage battery 51 through a part of wire 50, wire 52, contact 35, contact 36, wire 54, contact 55, 35 contact arm 42, wire 43, cylinder 44, spark plug 45, a portion of wire 46, coil 47, a portion of wire 46, and through a portion of wire 38 back to the opposite pole of the storage battery. In starting the engine, as 40 is well known, the contact arm 42 is first thrown to engage the pole 55 so that current is obtained from the storage battery and after the engine is started the contact arm is swung to engage the pole 40 thus 45 obtaining current from the magneto. This is the usual construction and no further explanation is deemed necessary, other than to state that when the actuating member 6 is swung to the right, to assume the position shown in the drawing, the contact 30 disengages contact 31 and contact 35 disengages contact 36, whereby the magneto and storage battery circuits are opened at those 50 points and current cannot be secured for starting the engine.

When the actuating member 6 is moved to the position shown in the drawing, the bar 9 has its lower end swung to the left and thereby contacts with the periphery of 60 the fly-wheel. If the engine is now cranked, the fly-wheel is turned which rotates the pulley 10. The rotation of the pulley 10 revolves the cam 17, causing the rod 15 to move upwardly. This movement of the

rod 15 turns the bell crank lever 18 upon its 65 pivot and shifts the rod 21 to the left, swinging the bell crank lever 23 upon this pivot 24 and bringing contact 25 into engagement with contact 26, thus closing the circuit to cause the bell 56 to ring. In 70 this closed signal circuit current flows from one side of the source of current 51 through a portion of the wire 50, contact 25, contact 26, a portion of the wire 38, bell 56, and a portion of the wire 38 back to the opposite pole of the storage battery 51. It is thus apparent that the bell 56 will be made 75 to intermittently operate or ring.

It is to be understood that the form of my invention herewith shown and described 80 is to be taken as a preferred example of the same, and that various changes in the shape, size, and arrangement of parts may be resorted to without departing from the spirit of the invention or the scope of the sub- 85 joined claims.

Having thus described my invention, I claim:

1. The combination with the ignition circuit of an automobile engine, of an alarm 90 circuit, circuit closing means for said circuits, means engageable with the engine fly-wheel for closing the alarm circuit closing means, and a common member for causing engagement of said last mentioned means 95 with the engine fly wheel and for opening the ignition circuit closing means.

2. The combination with the ignition circuit of a combustion engine, of an alarm circuit, closing means for said circuits, a reciprocal rod connected to one of said circuit closures, means engageable with the engine fly wheel for imparting movement to said reciprocal rod, and a common operating member for causing engagement of the last 105 mentioned means with the engine fly wheel and for opening the closing means of the ignition circuit.

3. In apparatus of the character described, the combination with the ignition 110 circuit of an automobile engine, of an alarm circuit, a member adapted to be brought into contact with the fly-wheel of the engine, means including an actuating member to open the ignition circuit and shift the first named member into contact with the fly-wheel, and means operated by the first named member to close the alarm circuit.

4. In apparatus of the character described, the combination with a storage battery circuit, of a magneto circuit, an alarm circuit connected with the storage battery circuit, a switch in the storage battery circuit, a switch in the magneto circuit, a 125 switch in the alarm circuit, an actuating member connected with the first two named switches to operate them, a movable sup-

port arranged near the fly-wheel of the engine and connected with the actuating member to be shifted thereby, a friction pulley carried by the movable support to contact 5 with the fly-wheel, and means actuated by the friction pulley to operate the third named switch.

In testimony whereof I affix my signature in presence of two witnesses.

LEONARD BROWN.
